(57) **CLAIM**

The ornamental design for a three-way luminous wall lamp, as shown and described.

DESCRIPTION

FIG. 1 is a front, right, top perspective view of a three-way luminous wall lamp showing my new design;

FIG. 2 is a back, right, bottom perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is an enlarged view of the encircled area 9 of FIG. 1;

FIG. 10 is an enlarged view of the encircled area 10 of FIG. 3;

FIG. 11 is an enlarged view of the encircled area 11 of FIG. 8; and,

FIG. 12 is an enlarged view of the encircled area 12 of FIG. 8.

The broken lines shown on the drawings depict portions of the three-way luminous wall lamp that form no part of the claimed design. The dot-dash lines depict the enlarged view boundaries that do not form part of the claimed design.

1 Claim, 11 Drawing Sheets
